Att.

UNITED STATES PATENT OFFICE.

SHERMAN T. KUNKEL, OF LOS ANGELES, CALIFORNIA.

GAUGE-COCK-OPERATING TOOL.

1,422,771.

Specification of Letters Patent.

Patented July 11, 1922.

Application filed December 3, 1921. Serial No. 519,670.

To all whom it may concern:

Be it known that I, SHERMAN T. KUNKEL, a citizen of the United States, residing at Los Angeles, in the county of Los Angeles 5 and State of California, have invented new and useful Improvements in Gauge-Cock-Operating Tools, of which the following is a specification.

My invention relates to tools for operating 10 oil gauge cocks of the Ford type, and it is a purpose of my invention to provide a tool of this character which is adapted to be associated with an automobile in such manner that it can be operated from a point at the 15 side of the car so as to eliminate the necessity of the operator crawling under the car to open the cocks, as is now the present practice. It is also a purpose of my invention to provide a gauge cock operating tool 20 which can be associated with an automobile to constitute an integral part thereof and to be securely held against rattling.

I will describe one form of tool embodying my invention and will then point out the 25 novel features thereof in claim.

In the accompanying drawings,

Figure 1 is a view showing a portion of a Ford automobile having applied thereto one form of tool embodying my invention.

Fig. 2 is a fragmentary sectional view 30 of certain parts of the automobile shown in Fig. 1, with the tool in applied position.

Fig. 3 is an enlarged detail view showing the socket end of the tool shown in the pre- 35 ceding views.

Referring specifically to the drawings in which similar reference characters refer to similar parts, my invention, in its present embodiment, comprises a shank 15 formed 40 of relatively rigid wire bent at right angles at one end to provide a handle 16, while its opposite end is bent at right angles as indicated at 17 where it is then coiled upon itself to provide a socket 18 disposed at right angles to the shank 15. The shank carries a coiled expandable spring 19 which is confined between the handle 16 and a cotter pin 20 extended through a suitable opening formed in the shank.

In Figs. 1 and 2, I have shown a Ford 50 type of magneto casing designated at K and which, as usual, is provided with a lower gauge cock C and an upper gauge cock C' which are designed for the purpose of determining the amount of oil contained in the casing.

In the applied position of the tool as shown in Figs. 1 and 2, the shank 15 is slidably fitted in an opening formed in the running board apron designated at A. This 60 opening is disposed in horizontal alinement with the lower gauge cock C, and with the tool in applied position the handle 16 projects to the outer side of the apron A to allow of the ready manipulation of the tool 65 from a point exterior of the car body. The spring 19 is located between the cotter pin and the inner side of the apron A so that it normally tends to urge the tool downwardly toward the casing K. The socket 18 is adapted 70 to receive either of the handles 21 of the cocks C and C', but normally receives the handle of the cock C, as this is the cock which is most frequently used in determining the amount of oil within the casing. 75 Under the action of the spring 19 the socket 18 is held in engagement with either of the handles 21 so that all that is necessary to effect an opening of the cocks is to rotate the handle 16 thereby imparting a similar 80 movement of the socket 18 to turn the handle 21. The opening in the apron A is sufficiently wide to allow of the tool being shifted to the handle of either cock as is shown in Fig. 2, and when the tool is not 85 in operation it assumes a horizontal position with the socket receiving the handle of the cock C. The spring 19 not only serves to facilitate the manipulation of the tool, but prevents the latter from rattling.

Although I have herein shown and described only one form of gauge cock operating tool embodying my invention, it is to be understood that various changes and modifications may be made herein without 95 departing from the spirit of the invention and the spirit and scope of the appended claim.

I claim as my invention:

In combination, a magneto casing having 100 gauge cocks arranged one above the other, a running board apron having an opening in horizontal alinement with one of the gauge cocks, and an operating tool movably sustained in the opening to be alternately 105 applied to the cocks for actuating the latter, and means for urging the tool inwardly toward said cocks.

In testimony whereof I have signed my name to this specification.

SHERMAN T. KUNKEL.
